UNITED STATES PATENT OFFICE.

ISAAC HODGSON AND WILLIAM H. BROWN, OF INDIANAPOLIS, INDIANA.

IMPROVEMENT IN FIRE-PROOF ROOFS.

Specification forming part of Letters Patent No. 129,826, dated July 23, 1872.

To all whom it may concern:

Be it known that we, ISAAC HODGSON and WILLIAM H. BROWN, of Indianapolis, in the county of Marion and State of Indiana, have jointly invented certain new and useful Improvements in Tile Covering and Construction of Fire-Proof Roofs, of which the following is a specification:

Our invention relates to the construction of the covering for fire-proof roofs; and the said invention consists of a new method of covering the roofs of building with tiles, glass, or other materials by means of grooved and flanged rolled iron laths, to which the said tiles or other material are firmly secured at both their upper and lower ends; the object of said invention being to construct a roof which is entirely fire-proof, perfectly secure against storms, rendered water-tight, and is comparatively less expensive than hitherto constructed.

In the accompanying drawing, Figure 1 represents a view in perspective of a portion of a fire-proof tile roof embracing our invention. Fig. 2 represents a section of the same, showing the method of securing the tiles to the metallic laths. Fig. 3 represents (on an enlarged scale) a section of one of the metallic laths and a portion of two courses of tile, showing more clearly the manner of securing them to the laths; and Fig. 4 represents a cross-section through one of the perpendicular joints of two contiguous tiles, showing the manner of rendering the joints water-tight.

General Description.

A is the rafter, which may be of iron or wood, or which may represent the top cord of a roof-truss. B is the rolled iron lath, flanged at its lower edge for the purpose of securing the same to the rafter A aforesaid, and grooved and flanged at its upper edge for the reception of the tiles C, which may be of well-burned clay or other material, or, where necessary for the purpose of lighting, of glass, and of such dimensions as may be desired. D represents lugs cast upon the under side of the tiles C, one near each edge of the same, and near their lower ends, when deemed necessary. The projection forming the lugs may be continued throughout the length of the tiles, thereby adding to their strength. The lugs

are for the purpose of securing the lower ends of the tiles to the lath B by catching against and under the flange E. F is a tongue on the upper end of the tiles, the same being made to fit into the groove G of the lath B, and being firmly held in position by the flanges H and I. J are triangular ribs, cast one upon each edge of the tile on the upper side, and extending from the lower end of the tile to the shoulder of the tongue F. K is a triangular slot cast in the under side of the lower end of the tile C to receive the triangular ribs J aforesaid. L is a metallic saddle for making tight the perpendicular joints between tiles, the same being held in position by the wires M and the slot K.

The rolled laths B may be of any depth of section required, and according to the distance between supports, and may be riveted to rafters, or to the top chord of the roof-trusses direct, thereby obviating the necessity for rafters and purlins, the laths being set at such distances between centers as that, when the tongue F of the tile C is inserted in the groove G, between the flanges H and I, there will be just sufficient room for the lugs D to clear the flange E. The tiles C will then, of their own weight, slide down and firmly lock the lugs D under the flange E, and, in so doing, will leave the channel N across their upper ends. After laying the course through the said channel N may be filled with putty, plaster Paris, or other plastic material. The next course of tiles being proceeded with in like manner, the triangular groove P, crossing the under side of the tiles C, will be pressed down upon the plastic material in the channel N by the act of sliding into position the lugs D, thus forming an effectual barrier to the backing of water. The saddle L may be made of sheet-copper, galvanized iron, or other material, and will be bent at an angle somewhat less than the angles formed by the junction of the ribs J, and will be made in length equal to the length of the said ribs. The upper end of the saddle is inserted in the space between the said ribs J and the slot K in the lower end of the tiles C. A copper-wire staple is then passed through openings in the saddle L made to receive it near its lower end, or at intervals where necessary, and through corresponding slots Q formed in the edges of the

tiles for the purpose, and firmly twisted round a short piece of wire placed crosswise of the tile on the under side, thus drawing the edges of the saddle tight upon the tiles, forming a perfect water-joint. When necessary the edges of the tiles may be beveled slightly open at the top and close at the bottom, and the space between may be filled with putty, as at O, before putting on the saddle L.

The advantages of this over other modes of roofing are, that the laths B may be applied directly to the trusses of the roof, thereby saving the cost of purlins and rafters, the distance between laths being only limited by the size at which the tiles can be conveniently burned, or glass or other material obtained. The tiles, being firmly held at both ends, cannot possibly be blown off the roof. Sky-lights may be introduced in any part of a roof by having glass tiles of the same dimensions as the roofing-tiles, and working them in, after the same manner as the tiles, at such places as may be necessary, the difference being scarcely perceptible.

Should a tile be broken from any cause, or should the gutters or valleys of the roof require renewing, the course of tile bordering upon the same may be entirely removed, new gutters inserted, and the tiles replaced with the greatest facility. The saddle L may be

drawn so tightly, by twisting the wires M, as to render the passage of water through the joints between tiles practically impossible.

Having described our invention, we claim—

1. In a fire-proof tile roof, the rolled laths B, with the flanges R, E, I, and H, and the groove G, essentially as and for the purposes hereinbefore set forth.

2. The combination of the lugs D of the tile, constructed as described, with the flange E of the metallic laths B, as and for the purpose described.

3. The combination of the tongue F and lug D of the tile C with the flanges H I E and groove G of the metallic laths B, as and for the purpose described.

4. The tile, secured at both ends by means of the flanges E, H, and I, the groove G, tongue F, and lug D, as and for the purpose set forth.

5. The arrangement of the sealing-channel N between the shoulder of the groove K and the upper flange H of the metallic lath B, and beneath the channel P, as described, and shown in Fig. 3 of the drawing.

ISAAC HODGSON,
WILLIAM H. BROWN.
